UNITED STATES PATENT OFFICE.

WILLIAM MEYER, OF CHICAGO, ILLINOIS.

SPARK-GAP.

1,316,916.

Specification of Letters Patent. Patented Sept. 23, 1919.

Application filed September 11, 1917. Serial No. 190,858.

To all whom it may concern:

Be it known that I, WILLIAM MEYER, a citizen of the United States, residing at Chicago, in the county of Cook and State 5 of Illinois, have invented a certain new and useful Improvement in Spark-Gaps, of which the following is a full, clear, concise, and exact description, reference being had to the accompanying drawings, forming a 10 part of this specification.

My invention relates to spark gaps. Devices of this class are employed in wireless telegraphy, X-ray, fluoroscopic and electro-therapeutic work, as is well understood by 15 those skilled in the art.

The common type of spark gap that has heretofore been employed comprises a pair of cylindrical metal plugs placed axially in line with each other with their square 20 radial faces substantially parallel to each other, these cylinders or plugs being provided with annular radiating fins or flanges for dissipating the heat generated in the gap.

25 I have found this type of gap to be very unreliable where a steady current is required and this is particularly noticeable where a relatively feeble current is employed. When the electrodes are brought 30 to the proper distance apart from each other to cause the spark to pass and are then left in that condition in a few moments the condition of the spark gap is so varied apparently by the electric discharge itself that 35 the sparks cease to pass.

I have experimented with the various forms of electrodes and find that the square ended cylindrical electrode is very poorly adapted to this work.

40 According to my invention I provide electrodes one of which, at least, has a series of substantially vertical fins of a good heat conducting and current conducting metal, these fins being all faced off to have their 45 front edges lying in the same plane so that a great number of edges are represented. In the preferred form of my invention I employ two such electrodes with the fins or ribs of one electrode lying in line with 50 the spaces between the fins or ridges of the other electrode. Suitable means is provided for adjusting the two electrodes toward and from each other without rotating them. As a consequence a series of parallel spark

gaps all of substantially the same length are 55 formed in multiple. Another important effect which can be observed is that the vertical channels formed by the vertical fins or ridges provide small vertical air chutes or chimneys which carry away the heat generated in the gap and at the same time serve to extinguish each spark promptly and effectively.

I shall now describe in detail in connection with the accompanying drawing which 65 forms a part of the specification one particular embodiment of my invention to apprise those skilled in the art how to practise and secure the advantages of the same.

Figure 1 is a front elevation of the spark 70 gap of my invention showing the water jacket for one of the electrodes in longitudinal sections;

Fig. 2 is a plan view of the device of Fig. 1;

Fig. 3 is a modified arrangement of the electrodes; and

Fig. 4 is a still further modified form of the electrodes.

The spark gap is formed between the electrodes 1 and 2, which comprise rectangular prismatic blocks of metal, such as brass or bronze or other cuprous metal having a series of fins projecting from the front edges thereof. In the particular embodiment illustrated, the fins 3 are composed of narrow strips of silver set edgewise into grooves milled into the front faces of the blocks 1 and 2. The spaces 4 between the fins 3 are slightly greater in width by a few thousandths of an inch than the fins themselves. The fins on the block 1 are arranged opposite the spaces 4 on the block 2 so that the fins 3 of the blocks may slide past each other. Thus there are formed a multitude 80 of minute spark gaps all in parallel with each other. I find it generally unnecessary to actually intermesh the fins 3 as it appears that the corners or sharp edges of these fins are the most efficient spark producers and by 85 merely bringing the sharp corner of one electrode adjacent the sharp corner of another electrode the same effect is obtained, namely, a multitude of small spark gaps all 90 in parallel.

I have also employed the arrangement shown in Fig. 3 in which the fins 3 are placed substantially opposite each other,

that is to say, in line with each other. While this arrangement gives very good results I prefer the arrangement shown in Figs. 1 and 2, as I find the latter slightly 5 more reliable.

The arrangement shown in Fig. 4 operates fairly satisfactorily, the fins 3 in this case coöperating with the front face 6 of the solid electrode 5. The same chimney effect 10 is present though in less degree. The plurality of sharp edges is also present, though in less degree. While the device shown in Figs. 1 and 2 is the preferred form of the invention, I wish to be protected in such 15 modifications as illustrated in Figs. 3 and 4 and as will occur to those skilled in the art without further exercise of invention.

The structure shown in Figs. 1 and 2 embodies other inventive conceptions, all tending 20 to the proper use of the spark gap described. The electrode blocks 1 and 2 are mounted upon the ends of threaded rods 7 passing through the tubes 8 of the water jacket 9. Each of the water jackets 9 and 25 10 is formed of a cylindrical shell 11 having a filling opening 12 at the top thereof for filling the water jacket with water or other cooling fluid. The ends of the cylinders 11 are closed as by means of the heads 13—14 30 through which the tube 8 passes axially. The front faces of the inner heads 13 and 25 are grooved or recessed as shown at 15 to prevent turning of the blocks 1 and 2. The bolts or rods 7 which are fastened to the 35 blocks 1 and 2 are provided at their rear ends with thumb nuts 16.

The heads 13 and 14 of the water jacket 9 are provided with feet 17 by which this water jacket is mounted upon the insulating 40 base 18. The electrode 2 is connected through the water jacket and through the bolts 7 and one of the feet 17 with a terminal bolt 19. This bolt 19 is in turn connected with one conductor 20 of the system. 45 The bolt 19 secures the insulating base 18 upon a further support such as a part of the cabinet or wooden casing on which this spark gap is mounted.

The other water jacket 10 with its electrode 1 is adjustable toward and away from the electrode 2 and water jacket just described. To this end a pair of flat slides 22 and 23 are set edgewise upon the supporting posts or pillars 24 and the heads 25 and 26 55 are provided with lugs 27 having grooves coöperating with the guides 22—23.

The electrode 1 is connected through the water jacket, the lugs 27, guides 22 and 23 and through the post 24 with a terminal 60 bolt 28 and a wire 29 of the system. The electrode 1 is made adjustable along the guides 22 and 23 by means of the adjusting screw 30 and insulating handle 31. The screw 30 is mounted in a post 32, this post 65 being split to provide the proper degree of

friction for holding the adjusting screw 30. The end of the screw 30 is held by a strap 33 in a recess in the head 26.

I do not intend to be limited to the precise features of construction shown and described.

I claim:

1. In combination, a pair of electrodes, one of said electrodes comprising a block of metal having a series of vertical parallel 75 fins projecting from the face thereof, said fins having vertical sparking edges and forming a series of vertical parallel air passages between said fins, said air passages being of uniform area from end to end. 80

2. In combination, a pair of electrodes, each of said electrodes comprising a block of metal having a series of vertical parallel fins projecting from the face thereof, said fins having vertical sparking edges and 85 forming a series of vertical parallel air passages between said fins, said air passages being of uniform area from end to end, and means for guiding the fins on one electrode into the air passages between the fins of the 90 other electrode.

3. In combination, a pair of electrodes, one of said electrodes comprising a block of metal having a plurality of vertical parallel 95 fins projecting from the face thereof, said fins consisting of a series of prismatic strips presenting sharp sparking edges to the opposing electrode, said prismatic strips defining a series of vertical parallel air passages between said strips, said air passages 100 being of uniform area from end to end.

4. In combination, a pair of electrodes, each of said electrodes comprising a block of metal having a plurality of vertical parallel fins, projecting from the face thereof, 105 said fins consisting of a series of prismatic strips, the opposing faces of each series of strips being flat and presenting sharp sparking edges, said prismatic strips defining a series of vertical parallel air passages between said strips, said air passages being of uniform area from end to end. 110

5. In combination, a supporting base, a pair of water jackets mounted on said base, and spark gap electrodes on said water 115 jackets, one of said electrodes comprising a series of vertical sparking fins having vertical air passages between said fins, said water jackets being alined substantially horizontally on said base to permit free circulation of air up through said vertical air passages.

6. In combination, a spark gap comprising a pair of metal electrodes having vertical metal ridges projecting therefrom, 125 means for guiding the ridges on one electrode into the spaces between ridges on the other electrode, and means for adjusting the electrodes with respect to each other.

7. In combination, a cylindrical metallic 130

- jacket having an axial hollow tube passing therethrough, a rod passing through said tube, an electrode secured to one end of the rod, means at the opposite end of the rod for holding the electrode against the head of the jacket, means for mounting the jacket upon a support, said jacket being adapted to be substantially filled with water, and a conductor connected to said supporting means.
8. In combination, a supporting base, a pair of guides mounted upon said base, a water jacket comprising a metallic drum having an electrode upon one head of the drum, a post mounted on the supporting base, and an adjusting screw connected between the post and the other head of the drum.
9. An electrode for a spark gap comprising a block of conducting metal, a series of vertical parallel sided fins projecting from the face thereof, the fins being parallel with each other and spaced apart slightly more than the thickness of the fins, thereby forming a series of air channels between the fins which are rectangular in cross section and uniform in area from end to end. 25
10. In a device of the kind described, a pair of electrodes, each thereof having a series of vertical parallel fins projecting from the face of the electrodes, fins comprising parallel strips spaced apart slightly more than the thickness of the strips, thereby forming a series of air channels between the fins which are uniform in area from end to end, the fins of one electrode 30 being arranged opposite to the air channels of the other electrode and means for adjusting the electrodes with respect to each other to change the length of the spark gap. 35
- In witness whereof, I hereunto subscribe 40
my name this 7th day of September, A. D.
1917.

WILLIAM MEYER.
